UNITED STATES PATENT OFFICE.

WILHELM SIEGFRIED, OF ERFURT, GERMANY.

LABEL-FASTENER.

1,127,298.

Specification of Letters Patent.

Patented Feb. 2, 1915.

Application filed April 6, 1914. Serial No. 830,004.

To all whom it may concern:

Be it known that I, WILHELM SIEGFRIED, manufacturer, a subject of the King of Prussia, residing at Erfurt, in the Kingdom of Prussia, in Germany, have invented certain new and useful Improvements in or Relating to Label-Fasteners, of which the following is a specification.

The label fastener provided with protection for the fastening pin according to my invention, is arranged so that the point of the pin is completely concealed whereby any injury to the hand or to the material to which the label is pinned, or to the adjoining materials, is completely prevented. The point of the pin itself is protected by bending a tongue or flap of the label at an angle rearward, as well as by carrying the stem or wire of the pin over the flap and securing it to the latter, so as to prevent it from turning laterally, whereby the pin in an unused label, always stands normal to the surface of the label and cannot turn over. After the point of the pin has been stuck through the material and bent upward, the flap is pressed over the bent pin, and the point of the latter is thus completely covered.

Protection for the pin is therefore obtained by means of a tongue or flap of the label, bent at an angle and in one piece with the label itself. The said flap is stiffened by the wire which forms a branch or stem of the pin, so that the bent flap cannot straighten out, and thus the protection of the pin is permanently insured. Moreover, by bending the stem of the pin upward or downward on the inner face of the label, a supporting layer is formed, and by bending the other end of the wire over the flap bent rearward at an angle, the pin is held fast so that it cannot turn laterally. In practical use, only the point of the pin therefore is stuck into the material to be marked, the said point being bent upward and the flap of the label bent over it. Owing to its being strengthened by the wire, the bent flap is prevented from bending again, and the point of the pin is permanently covered by the flap so that it does not project and cannot lead either to injuries to the finger or to such materials as may be placed on the material labeled.

The invention is illustrated in the accompanying drawings, in which:—

Figures 1 and 2 show a form wherein the label is provided with a single fastening pin,

Fig. 2 being a plan view and Fig. 1 being a central longitudinal section on the line A—B of Fig. 2; Figs. 3, 4 and 5 show a slightly modified form wherein the label is provided with a pair of fastening pins, Fig. 5 being a plan view, Fig. 3 being a central longitudinal sectional view on the line G—H of Fig. 5, and Fig. 4 being a cross-sectional view on the line C—D of Fig. 5; Figs. 6, 7, 8 and 9 show a further modified construction, Fig. 8 being a plan view, Fig. 6 being a central longitudinal sectional view on the line I—K of Fig. 8, Fig. 7 being a cross-sectional view on the line E—F of Fig. 8, and Fig. 9 being a central longitudinal sectional view showing the label in attached relation.

Similar characters of reference designate corresponding parts throughout the several views.

Referring to Figs. 1 and 2: The label 1 is provided with a tongue or flap 2 which is in one piece with the label proper and is bent rearward. The wire 3 is carried through the label toward the inner side thereof, and provided with an outward bend 4 parallel to and lying against the label proper and from which projects the pointed shank, (Figs. 1 and 2). The wire 3 is then carried on the outside of the label and upward along the flap 2 and clenched to the latter. Owing to one end of the wire being bent at an angle over the flap, a firm position of the pin is insured. In the construction shown in Figs. 1 and 2, the wire is passed through the flap and bent in such a manner that it is firmly secured to the flap.

Figs. 3 to 5 show a construction wherein the label, instead of being provided with one pin, as in Figs. 1 to 3, is provided with two pins arranged in parallel relation and each being generally similar to the single pin shown in Figs. 1 to 3. These figures show a further modification in that the bend, as 4^a, from which the shank 5 projects, is directed toward the flap 2 instead of away from it, as in the bend 4 in the embodiment shown in Figs. 1 to 3.

The modified construction shown in Figs. 6 to 9, like the construction shown in Figs. 3 and 4, embodies two fastening pins, each pin being shown as of the same construction as the fastening pins in Figs. 3 and 4. According to Figs. 6 to 9, however, the ends of the fastening pins which are clenched to the label 2, are connected, adjacent the inner face of said label, by an integral bar 7 which

extends transversely of the label. Fig. 9 shows the relation of the label to the fabric 9 to which the label is secured. Fig. 9 shows the label constructed according to the modification shown in Figs. 6 to 8. The relation of the label to the fabric is the same in all cases, however, in that the flap 2 overlies the shank 5 and the latter is bent inwardly toward the flap 2 and parallel to the label 1. 10 The label in all the embodiments of the invention may be provided with a facing 8 which covers both the label proper and the flap, and also the exposed portions of the fastening pin or wire and thus assists in 15 curing the wire to the label and the flap.

What I claim is:

In combination, a label having a flap at one end thereof and standing at an angle thereto and a wire extending along the out-

side of the flap and of the label for a part 20 of the length of the latter, the wire being clenched to the flap and having one end extending through the label, bent parallel to the label to lie against the same and provided with a pointed shank extending from 25 said bent portion normal to the plane of the label, the material of the label being flexible so that the flap may be turned against the body of the label to overlie and conceal the pointed end of said shank. 30

In testimony whereof I have hereunto set my hand in presence of two subscribing witnesses.

WILHELM SIEGFRIED.
